UNITED STATES PATENT OFFICE

ERTHOLD C. JANKE, OF MILWAUKEE, WISCONSIN, ASSIGNOR TO JAYEM MANUFACTURING COMPANY, OF MILWAUKEE, WISCONSIN, A CORPORATION OF WISCONSIN

BOOT

Application filed July 27, 1925. Serial No. 46,315.

The invention relates to boots and shoes and more particularly to improvements in the type of fastening means therefor disclosed in my co-pending application for shoes, Serial No. 704,191, filed April 4, 1924.

The use of a multiple-operated fastener on a high boot, in conjunction with a lacing for fitting the boot to the foot, as disclosed in the above application, has been found very convenient as the operation of placing the boot on the foot and removing it therefrom is greatly simplified. The boot may be properly fitted to the foot by the use of the lacing and the fastener is so flexible that it does not cause any discomfort. It has been found desirable to apply this fastening means to ordinary lacing boots and to permit replacement on boots in which the fastener or adjacent parts have become defective.

It is an object of the present invention to provide an attachment for boots comprising a fastener strip adapted to receive eyelets for a lacing and including a multiple-operated fastener, whereby the fastener strip may be readily applied to a boot without encountering the difficulties met with in mounting the fastening elements directly to the upper.

Another object of the invention is to provide a novel form of gusset for the boot which will facilitate manipulation and avoid discomfort.

A further object of the invention is to so place the fastener on the boot in a position affording the greatest ease of entrance and removal of the foot and presenting a neat appearance.

In the accompanying drawings,

Fig. 1 is a perspective view of a boot embodying the fastening strip of this invention;

Fig. 2 is a fragmentary sectional view thereof taken on the line 2—2 of Fig. 1; and

Fig. 3 is a plan view of a fastener strip before its application to a boot.

In these drawings, 10 indicates a boot in which the upper 11 is parted at its forward portion, the outer quarter of the upper being provided with a row of eyelets 12 for a centrally disposed or front lacing 13. To cor-

respond with the eyelets 12, an inner row of eyelets 14 is placed in a fastener strip 15 of leather or other suitable material, which is provided with a longitudinally extending slot 16 to form spaced narrow ribbons 17 and 18 on its opposite sides joined at their lower ends. The eyelets 12 and 14 are arranged directly opposite each other in pairs to receive the front lacing 13 which is a crossed lacing to insure retention of adjustment.

The fastener employed for closing this slot is of the multiple-operated separable type, a well known variety being illustrated, in which flexible stringers 19 of fabric or leather attached to the ribbons 17 and 18 at the edges of the slot 16 are provided with interlocking members 20 secured thereto in alternate relation. The interlocking members are engaged and released by a runner 21 which serves to spread the members to permit their meshing or withdrawal. The runner is conveniently provided with a tab 22 to afford a fingerhold, whereby the runner may be moved up to afford a closure and down to release the interlocking members.

One of the flexible stringers 19 is sewn to the inner side of the eyeleted ribbon 17 and a facing 23 may be sewn at the inside thereof by the same stitching. The other stringer is secured to the ribbon 18, as by a single central line of stitching 24.

When the fastener strip is applied to a boot originally employing only a lacing, a strip of leather is removed from the forward portion of the inside quarter of the boot. The ribbon 18 of the fastener strip is then sewn by lines of stitching 25 to the edge of the quarter left after removing the strip of leather above noted. A new or modified gusset 26 is furnished in which one edge is secured to the upper by the stitching 25 and the opposite end portion folded with its edge secured to the upper along the row of eyelets 12, thus furnishing a closed gusset in which there is but one fold disposed at the outside quarter of the boot. When the spacing of the eyelets 12 is unknown the fastening strip 15 is preferably furnished without eyelets, so that they may be later installed to correspond with the original eyelets 12.

When the fastener strip is applied to a boot originally employing a similar fastener which has become defective, the old fastener is cut away along the inside stringer at the 5 edge of the slot in the quarter receiving the fastener, thus leaving a stringer part 19' of the original fastener attached to the upper, as seen in Fig. 2. The gusset 26 in a boot originally employing the fastener is preferably 10 fastened in the manner indicated in Fig. 2, as above described, so that it requires no alteration. The fastener strip 15 is then sewn to the upper by seams 25 in the same manner as above described. If the spacing of the eyelets on the original boot is known, the fastener strip may be furnished equipped with eyelets. In each instance, the ribbon 18 of the fastener strip may be suitably skived at its edges so that when sewn to the boot it will 15 present a neat appearance. It will be seen that the operation of applying the fastener strip to a boot is comparatively simple and may be done by any cobbler, as the fastener assembly is sufficiently rigid to permit accurate sewing, and thus obviates the necessity 20 for attaching the flexible stringers of the fastener to adjacent leather parts, which is a factory operation requiring considerable skill. The leather ribbons are preferably 25 curved at intermediate portions to conform to the shape of the upper, and maintain the flexible stringers 19 in a corresponding shape.

The fastener strip is preferably provided at the inner quarter of the upper adjacent the 30 lacing for the greatest effectiveness, as the lower terminus of the fastener is then substantially in line with the highest portion of the instep at the first metatarsal bone to afford the largest possible opening for insertion of the foot into the boot.

As the lacing 13 is disposed centrally of the forward portion of the boot, the symmetry and appearance of the boot will not be impaired by variations of the width of the leg 35 in the boot, and the term front lacing, as hereinafter noted, defines a lacing in such position.

The fastener strip is made sufficiently narrow so that it will not bear on the adjacent 40 projecting ankle bone and cause discomfort. As only a single fastener is required and only one lacing is necessary, boots embodying the fasteners may be inexpensively manufactured. To insure smooth and easy operation 45 of the runner 21, a groove of ample depth is provided to form the fastener slot so that the runner will not press against the gusset during its travel.

The boot is placed on the foot with the separable fastener closed and the lacing open. 50 The gusset 26 is then smoothed to assume the position shown in Figs. 1 and 2 to present only a single fold at one side, and the lacing is then adjusted to obtain the proper fit and 55 then tied. For subsequent removal of the

boot the runner 21 is moved downwardly to release the interlocking members 20, whereupon the laced portion of the upper is swung outwardly from the foot to afford easy removal of the boot. Thereafter the boot is 70 placed on the foot with the separable fastener opened, the gusset being readily smoothed and adjusted by passing one hand through the opening left by the fasteners and moved along to properly position the fold. It is then 75 only necessary to move up the runner to effect closure of the upper, which requires but very little time as compared with a lacing operation, the lacing remaining in its initially adjusted position to insure a properly fitting 80 boot.

The term "boot", as herein used, includes shoe.

What I claim as new and desire to secure 85 by Letters Patent is:

1. An attachment for boots, comprising a multiple-operated separable fastener including a pair of flexible tapes having separable interlocking members fixedly secured thereto, and a leather fastener strip including spaced 90 ribbon portions joined at their lower ends and permanently secured longitudinally to the outer portions of said tapes, said ribbon portions having intermediate curves and possessing sufficient rigidity to define a pre-determined disposition of said flexible tapes. 95

2. An attachment for boots, comprising a slide controlled multiple-operated separable fastener including a pair of flexible tapes having separable interlocking members fixedly secured thereto, and a leather fastener strip including spaced ribbon portions joined at their lower ends and permanently secured longitudinally to the outer edge portions of 100 said tapes, and said ribbon portions possessing sufficient rigidity to define a predetermined disposition of said flexible tapes. 105

3. The combination, with a shoe having an upper provided with the usual row of eyelets along one of its spaced separable forward edges, of a pair of separable flexible strips one of which is secured inlapping relation to the other forward edge of the upper and the other of said strips being spaced laterally from the eyeleted forward edge of the upper and having eyelets corresponding in spacing to the shoe upper eyelets, a centrally-disposed lacing bridging said eyeleted edge of the upper and said eyeleted strip for fitting the boot on the foot, and slide-controlled 110 means for connecting said strips together. 115

4. An attachment for boots comprising a fastener strip including spaced substantially parallel ribbon portions joined at their lower ends, one of said ribbon portions adapted to be longitudinally secured to the upper of a boot and the other of which is adapted to be provided with eyelets to receive a lacing, and a slide-controlled multiple-operated separable fastener connecting the spaced ribbon 120 125 130

- portions of said fastener strip and including a pair of flexible tapes fixedly secured to said ribbon portions and separable interlocking members fixedly secured to said tapes.
- 5 5. An attachment for boots comprising a slide-controlled multiple-operated separable fastener including a pair of flexible tapes having separable interlocking members fixedly secured thereto, and a leather fastener strip
- 10 having spaced ribbon portions joined at their lower ends and permanently secured longitudinally to the outer edge portions of said tapes, one of said ribbon portions being adapted to receive eyelets to correspond with
- 15 eyelets on a boot for receiving a front central lacing and the other of said ribbon portions adapted to be longitudinally sewn to said upper whereby the application of said fastener to a boot is facilitated.
- 20 6. An attachment for boots comprising a slide-controlled multiple-operated separable fastener including a pair of flexible tapes having separable interlocking members fixedly secured thereto, and a leather fastener strip having spaced substantially parallel ribbon portions joined at their lower ends and permanently secured longitudinally to the outer edge portions of said tapes.

In testimony whereof, I affix my signature.
